UNITED STATES PATENT OFFICE.

GLENVILLE S. TREMAINE, OF WESTFIELD, NEW JERSEY.

COMBINATION CLOCK AND CALENDAR.

Application filed July 23, 1924. Serial No. 727,665.

This invention relates to what may be called a combination clock and calendar, a device particularly adapted to be placed on an office desk for the purpose of indicating the time of day and the correct date. The principal object of the invention is to provide a device of this character which is extremely simple in construction and operation and thoroughly reliable, one that can be depended upon to indicate the correct date thruout the entire year or any other period.

My invention includes a continuous strip of paper or other material bearing the successive dates, and means for advancing this strip so as to display the correct date thru an opening or window in a suitable casing. The invention includes means for advancing the strip of paper, and an escapement device which permits the advancing means to function at selected times. The escapement device is preferably, tho not necessarily, actuated by a clock mechanism; and the several parts of the improved device are arranged so that at certain times, for example, at midnight each day, the clock mechanism or other continuously operating device, actuates the escapement device to permit the calendar strip advancing means to advance the strip a predetermined distance to bring the next date into registration with the opening of the casing.

The various objects and advantages of this invention will be apparent upon considering the following detailed description, which is to be taken in conjunction with the accompanying drawings, in which—

Fig. 1 is a front elevation of one embodiment of the invention, parts being cut away to show the construction and arrangement of certain details.

Fig. 2 is a vertical sectional view of the embodiment shown in Fig. 1 taken at right angles to Fig. 1; and

Fig. 3 comprises four views (designated *a*, *b*, *c* and *d*) of the improved escapement mechanism, showing the construction and operation of this part of the invention.

My invention includes primarily means for displaying successive numbers representing the days of the year, together with such other information as the name of the month and the particular year, as may be desired. Accordingly, the embodiment of the invention illustrated in the accompanying drawings includes what may be called a calendar

strip 2. This strip is mounted within a casing 3, adapted to be placed upon an office desk or other support. The casing 3, shown in the accompanying drawings, contains a clock 1, the face of which is visible from the front of the casing. A portion of the calendar strip 2 is also visible from the front of the casing, thru an opening 10 therein. It is to be understood that the dates can be displayed by means other than a continuous strip of paper, and altho I prefer to use such a strip, yet certain features of the invention can be used to advantage with other forms of date displaying means.

The strip of paper 2 is initially wound upon a spool 4, carried by a shaft 5. This shaft is journaled in bearings 6, carried by the sides of the housing or casing 3. As the strip 2 leaves the spool 4, it passes between the guide rollers 7 and 8, which are preferably covered with rubber or felt so as to provide considerable friction between the rollers and the paper. The strip passes in the direction indicated by the arrows, to guide rods 9 arranged on opposite sides of an opening 80 or window 10 in the face 11 of the casing 3. The guiding means 9, which may be in the form of rods or rollers, are positioned so as to cause the strip 2 to expose a section thereof of definite length, to view thru the opening 10. After leaving the opening in the face of the casing the strip 2 is wound upon a second spool 12 supported by a shaft 13 journaled at one end thereof in a bearing 14 carried by one side of the casing 3. The other end of the shaft 13 is connected to a spring within a spring housing 15 of ordinary construction. This housing is carried by a second shaft 16 to which a winding key 17 is permanently or adjustably connected. One end 95 of the spring within the housing 15 is connected to the shaft 13 and the other end to the housing 15, as will be readily understood. By turning the key 17 the spring can be wound up, after which it serves as a means 100 for advancing the calendar strip 2, when this strip is released in the manner herein-after described. This spring also performs the function of winding the strip upon the spool 12. In other words, when the strip 2 is released, the spring within the housing 15 serves to pull the strip away from the spool 4, between the guide rollers 7 and 8, and around the guide rods 9 disposed near the opening in the face of the casing 3.

It is necessary to provide some means for regulating the action of the spring within the housing 15 so that the calendar strip is advanced at certain times only, for example, once each day. The means which I prefer to use in order to accomplish this result comprises an escapement device which operates upon the guide rollers 7 and 8 between which the calendar strip 2 passes as it leaves the spool 4. As pointed out above, there should be considerable friction between the guide rollers 7 and 8 and the strip of paper passing therebetween; and in order to insure proper tension on the paper at this point, I prefer to mount the upper guide roller 8 in vertically movable bearings 18, forced downward by springs 19, the tension of which can be adjusted by means of adjusting screws 20. The roller 8 is then, in reality, a friction roller adapted to press the strip of paper against the guide roller 7, and thus grip the paper.

While I prefer to mount the upper guide roller 8 in vertically movable bearings 18 forced downward by springs 19, the tension of which can be adjusted by means of adjusting screws 20, yet it is quite obvious that the roller 7 instead of the roller 8 could be provided with the spring mounting, or the cam 23 could be placed on the shaft of roller 7. If either of these alternative constructions is employed, there is no likelihood of the adjustable members interfering with the operation of the cam mechanism which might possibly occur where the preferred construction is employed, even tho the actual movement of the adjustable roller 8, would probably be found to be so slight that it would not interfere in any way with the proper operation of the cam mechanism.

A convenient manner in which to construct the several bearings above referred to is to provide a single casting 21 for each side of the housing 3, these castings to contain the bearings 6, the bearings 22 for the lower guide roll 7, and guides for the movable bearings 18 supporting the upper guide roll. The adjusting screws 20 can be threaded into these castings as shown in Fig. 1 so as to apply tension to the coil springs provided for each of the adjustable bearings 18.

The character of the springs which apply tension to the adjustable roller is, of course, immaterial and, therefore, flat springs can be employed to advantage instead of the coil springs just described, if it is so desired. Furthermore, the casing 21 could be made so as to provide bearings for the shafts 16 and 13.

From the above description it will be apparent that if some means is provided for holding the upper guide roller 8 stationary, except when it is necessary for the spring within the housing 15 to advance the

calendar strip, the necessary regulation of the strip advancing means will be provided. The escapement device which I have provided in order to accomplish this result includes an adjustable cam 23 mounted on the shaft 24 which carries the friction roller 8. A set screw 25 is provided in order to fix the cam in any desired position with respect to the shaft 24. A second cam 26, connected to the mechanism of the clock 1, is also provided; and two cam levers 27 and 28, carried by supports 29, are arranged to cooperate with these two cams. Each of these cam levers is provided with a follower at each end thereof. The upper ends of the cam levers 27 and 28 are normally forced toward each other by any suitable means, such as the spring 30, so as to cause the followers at the upper ends of these levers to engage the upper cam 26 at all times.

The upper cam 26 can of course be operated by any means which is the equivalent of the clock mechanism specifically mentioned herein; but in the particular embodiment of the invention illustrated in the accompanying drawings, this cam is geared to the shaft carrying the hour hand of the clock, a gear train having a 4 to 1 speed reduction being used. Accordingly, the cam 26 makes a half revolution every 24 hours. The gear ratio employed, of course, depends upon the speed of that part of the clock to which attachment is made, but in any case I prefer to use such a speed reduction that the cam 26 will turn thru one-half a revolution in 24 hours, for example, if attachment is made to the minute hand, the gear ratio should be 48:1.

The construction and operation of the escapement mechanism can best be understood by referring to Fig. 3 which shows several views of the cams 23 and 26 and the cam levers 27 and 28.

In the particular embodiment of invention shown in Fig. 3, the upper cam 26 is constructed so that one half of the cam surface is a cylindrical surface of relatively large radius, and the other half is in the form of a spiral as shown so as to provide a notch or offset portion 31 at one point on the face of the cam. The lower cam 23 is preferably constructed with surfaces complementary to those of the upper cam. That is, half of the cam surface of this lower cam is in the form of a cylindrical surface of comparatively small radius, while the other half is in the form of a spiral making a smooth connection with one end of the cylindrical portion of the cam and providing an offset portion or stop 32 at the other juncture with the cylindrical surface.

The four views comprising Fig. 3 show the operation of the cams during one complete revolution of the upper cam. This occurs once in two days. The cams are arranged

so that the strip advancing means is caused to operate at a certain time of the day, for example, at midnight, whereby the correct date is made to appear at the opening in the 5 face of the casing 3 at the proper time. The views *a* and *b* of Fig. 3 show the condition existing just before and just after midnight, the cams being arranged in the manner just described. In the first of these views the 10 cam followers engaging the upper cam 26 are far apart, one of these followers resting on the crest of the offset portion 31 of the cam. The lower cam 23 is held against rotation by virtue of the fact that 15 the follower at lower end of the lever 27 engages the stop 32. As soon as the upper cam 26 rotates to the position shown at *b*, and it will be remembered that the upper cam rotates continuously, the spring 30 20 causes the upper end of the lever 27 to drop suddenly into the notch 31. This pulls the follower at the lower end of the lever 27 out of engagement with the notch 32 carried by the lower cam, and thus releases the 25 calendar strip 2. The spring within the spring housing 15 carried by the shaft 16 (see Figs. 1 and 2) then causes the calendar strip 2 to advance until the cam 23 carried by the friction roller shaft 24 is rotated substantially 30 180 degrees and comes into engagement with the cam follower at the lower end of the lever 28, as shown at *b*. It is to be noted that while this action is taking place, the cam lever 28 does not move appreciably 35 and that is the reason why one half of the surface of the lower cam 23 is made cylindrical. This permits the follower at the lower end of the lever 28 to remain the same distance away from the center of the 40 cam 23 while this action takes place.

The positions shown at *c* and *d* of Fig. 3 represent the action of the escapement device on the following midnight. The upper cam 26 has rotated substantially 180 degrees in 45 a clockwise direction from the position shown at *b* and the follower at the upper end of the lever 28 is now on the crest of the notch or offset 31. The lower cam 23, and consequently the calendar strip 2, are 50 still held in the positions in which they were finally brought to rest by the action of the device twenty-four hours previously, as represented at *b*. As soon as the upper cam 26 moves to the position shown at *d*, the spring 30 causes the follower at the upper end of the lever 28 to drop suddenly 55 into the notch or offset portions 31 of the cam. This pulls the follower at the lower end of the lever 28 out of engagement with 60 the stop 32, thus permitting the calendar strip advancing means to advance the strip and rotate the cam 23 until it is brought to a stop by the follower at the lower end of the lever 27, as will be readily understood.

65 From the above description it will be ap-

parent that the function of the lower cam 23 is in reality that of a member fixed to the shaft 24 and having a stop thereon corresponding to the stop 32 shown in the drawings. This lower cam member can be constructed in any desired form, the only necessary requirement being a stop provided thereon and adapted to engage the followers carried by the levers 27 and 28.

70 My invention possesses a number of valuable features among which may be noted the readiness with which a new calendar strip can be inserted in the device, or the calendar strip adjusted if the successive sections of the strip do not register properly 75 with the opening in the face of the casing. In order to place a new calendar strip in the device it is merely necessary to insert a spool containing the strip, on to the shaft 5, thread the strip between the guide rollers 7 and 8 and around the rods 9, and fasten it to the winding spool 12. The lower cam 23 can be loosened from the shaft 24 to facilitate this operation. After the strip has been advanced to display any desired section thereof, the lower cam 23 can be turned until it is in proper position with respect to the upper cam 26 and then fixed to the shaft 24 in this position by tightening the set screw 25. If the successive sections of the 80 calendar strip 2 do not register properly with the opening 10 in the face of the casing 3, the cam 23 can be loosened by unscrewing the set screw 25 and the strip adjusted to secure proper registration with 85 the opening in the casing, after which the set screw 25 can be tightened.

90 Another distinct advantage of my invention arises from the simplicity of the mechanism employed. The number of moving parts is reduced to a minimum, and those which are employed consist of simple cams and cam levers which can be readily made at low cost, and which will practically never 95 get out of order after they have been assembled in the casing. Springs are used to hold the cam levers in position and to supply the power necessary to advance the calendar strip, and it is well known that such devices 100 are extremely reliable. By employing a gear train in connection with the spring which advances the calendar strip, a relatively powerful spring requiring winding only once or twice a year can be employed 105 within the casing 15. In this event the entire device does not require any attention except that ordinarily necessary to keep the 110 clock 1 running.

115 While the particular form of the invention illustrated in the accompanying drawings is that best adapted to be used on an office desk, yet it will be understood that the invention can be used to advantage in connection with any type of clock and accordingly it can be used in any place where a 120

clock is usually located. Furthermore the invention can be used for various purposes other than for the purpose of displaying a calendar strip. It can be used for registering time intervals of any duration or displaying any desired information at any desired time intervals. Various auxiliary devices could be used such as means for releasing the escapement device by hand.

10 It is to be understood that various changes in the details and in the construction and arrangement of the several parts of my invention can be made without departing from the spirit of the invention which is not limited to the particular embodiment illustrated and described, but includes such modifications thereof as fall within the scope of the appended claims. For example, a source of power other than the clock mechanism can be employed for continuously rotating the upper cam 26 at the desired rate; and in some cases it may be desirable to interconnect the clock mechanism or its equivalent with the spring within the housing 15, so that the operation of winding the clock automatically winds the spring which advances the calendar strip.

I claim:

1. In a calendar clock having a calendar strip, a spool adapted to have said strip wound thereon, means for advancing said strip, a guide roller for said strip, a friction roller adapted to press said strip against said guide roller; a member normally fixed with respect to one of said rollers, and having a stop thereon, a continuously operating mechanism, a cam operated by said mechanism, and a pair of levers cooperating with said cam and said member whereby said strip is permitted to advance at certain times only.
2. In a calendar clock having a calendar strip, a spool adapted to have said strip

wound thereon, means for advancing said strip, a guide roller for said strip, a friction roller adapted to press said strip against said guide roller; a member normally fixed with respect to said friction roller, and having a stop thereon, a continuously operating mechanism, a cam operated by said mechanism, a pair of levers cooperating with said cam and said member, and yielding means for holding said levers in contact with said cam.

3. A device of the type described, comprising a cam, means for rotating said cam continuously at a uniform rate, a member having a stop thereon, means tending to rotate said member, and a pair of levers engaging opposite sides of said cam and extending into close proximity to said member so that one of said levers temporarily engages the stop thereon, the several parts being arranged so that the movement of the cam causes the lever engaging said member to release the same and to permit it to rotate until the stop thereon engages the other lever.

4. A device of the class described, comprising a cam, means for rotating said cam continuously at a uniform rate, a member having a stop thereon, means tending to rotate said member, and a pair of levers pivoted between said cam and said member and having their ends engaging respectively the opposite sides of the cam and the member, one of said levers temporarily engaging the stop on said member, and the several parts being arranged so that the movement of the cam causes the lever engaging the stop on said member to release same and permit it to rotate until the stop thereon engages the other lever.

In testimony whereof I affix my signature.

GLENVILLE S. TREMAINE.
